ELECTRIC SHAVER

Hermann R. Schaefer, Bridgeport, Conn., assignor to
Sperry Rand Corporation, New York, N.Y.

Filed Nov. 16, 1970, Ser. No. 25,997

Term of patent 14 years

Int. Cl. D28—03

U.S. Cl. D95—3

Fig. 1

Fig. 2

Fig. 3

Fig. 4

Fig. 6.

Fig. 5.

Fig. 7.

FIG. 1 is a front, top and right side perspective view of a shaver showing my new design;
 FIG. 2 is a left side elevational view;
 FIG. 3 is a front elevational view;
 FIG. 4 is a right side elevational view;
 FIG. 5 is a rear elevational view;
 FIG. 6 is a top view; and
 FIG. 7 is a bottom view of the shaver.

Said shaver comprising a housing and cutter teeth. The characteristic features of my design resides in the configuration of said housing, and the drawing figures are shaded to indicate contrast in appearance.

I claim:

The ornamental design for an electric shaver, substantially as shown and described.
